Primary Examiner — Elizabeth A. Albert

(74) Attorney, Agent, or Firm — Zagorin Cave LLP;
Robert W. Holland(57) **CLAIM**

We claim the ornamental design for a pen, as shown and described.

DESCRIPTION

FIG. 1 is a front perspective view of the pen comprising the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 shows another perspective view thereof in use.
The broken lines in FIG. 9 are included to show environmental features that form no part of the claimed design.**1 Claim, 5 Drawing Sheets**FIG. 1

FIG. 2

FIG. 3

FIG. 4

FIG. 5

FIG. 6
